ROLL CHANGING APPARATUS FOR PRINTING PRESSES

Harold L. McCleery, Downers Grove, Ill., assignor to Allan J. Cline, Chicago, Ill.

Application April 25, 1932, Serial No. 607,315

18 Claims. (Cl. 242—58)

This invention relates to apparatus for supplying paper to printing presses and more particularly to means for making high speed pasters whereby the web from a nearly exhausted roll 5 may be joined to the web of a reserve roll with the press running at normal speed.

The general object of the invention is to provide an efficient apparatus for this purpose which may be applied to the type of roll apparatus now 10 in common use without undue complications or space requirements and which may be operated by workmen of ordinary skill, the operation being almost wholly automatic and leaving very little to the discretion of the workmen.

15 Among the special objects of the invention are to provide: novel automatic devices for controlling the positioning of a spare roll adjacent the traveling web from an expiring roll preliminary to making a paster; means electrically controlled from the press for bringing the spare roll to web speed; means operating with exceptional speed for effecting contact between the spare roll and the traveling web; means for timing the contact 20 with reference to the location of adhesive on the spare roll to insure that the initial contact will be at a point on the roll well in advance of the adhesive; and an accurately timed and quickly 25 acting cut-off device for severing the web from the expiring roll after the paster is made.

30 Other objects and advantages of the invention will be apparent as it is better understood from the following description, which, taken in connection with the accompanying drawings, discloses a preferred embodiment thereof.

35 Referring to the drawings:

Fig. 1 is an end view of a web roll support and roll changing apparatus in which my invention is embodied, the reserve roll being shown in the position which it assumes just prior to making a paster;

Fig. 2 is an elevational view taken lengthwise of the roll support from a plane at the left of Fig. 1;

Fig. 3 is a view of the reserve roll prepared for a roll change;

Fig. 3a is a detail view of the paper tab by which the leading end of the reserve roll is held to the body of the roll;

Fig. 4 is a diagrammatic view of certain of the press units and folders, showing the driving motors for the folders and the means whereby the starting belt drive motor of the roll changing apparatus may be commutated to either of adjacent folder drive motors; and

Fig. 5 is a wiring diagram of the electrical apparatus utilized in the invention.

Upon said drawings, I have shown a roll support in the form of a three-arm reel comprising fixed standards 6, each having a bearing 7 in the upper end thereof for a reel shaft 8 at the opposite ends of which are supported three-arm spiders 9, each arm 11 of which is provided with a bearing 12 for a spindle or paper chuck 13 for rotatably supporting a paper roll. In Fig. 1 of the drawings, the active or running roll which is nearly exhausted is indicated by the reference numeral 14, and a reserve roll is indicated by the numeral 15, it being understood that new rolls 10 may be loaded onto the arms shown at the right 15 in Fig. 1, so that there may always be one or more reserve rolls on the reel. The reel is adapted to be rotated for the purpose of positioning the rolls by means of a motor 16, the armature shaft 17 of which is supported in bearings 18 and 19 on the uprights 6 and carries a worm 21 meshing with a worm gear 22 carried by the reel shaft 3 at one end thereof as shown best in Fig. 2.

For the purpose of providing tension on the active roll, a plurality of tension straps 23 are provided, being secured at their lower ends to a rod 24 extending between the base portions of the uprights 6 and at their upper ends being wrapped around cams or drums 25 carried upon a shaft 26 which at one end has a sprocket 27 connected by a chain 28 with a sprocket 29 on a shaft 31 of a torque motor 32, which, through said sprocket 29, chain 28 and sprocket 27, exerts a constant turning strain or torque upon the shaft 26, tending to wind up the straps 23 on the drums 25. It will be understood that the invention is not confined to this particular form of tension device and that the showing thereof is only diagrammatic. It is well understood that some form of tension device must be provided in all apparatus of this character for the purpose of controlling the rotation of the active roll and preferably providing for emergency stops in case of a paper break or a sudden stop or slowing down of the press.

The web 33 from the active roll 14 passes over guide rollers 34 and 35 and between the press cylinders indicated by the reference numeral 36, 50 said cylinders being adapted to be driven through suitable gearing 37 from a drive motor 38 carried by support 39 secured to the press frame, one of said drive motors preferably being provided for each of the press units.

The normal running position of the active roll 14 is above the position in which it is shown in Fig. 1, and when this roll becomes nearly exhausted the reel may be turned by pressing an appropriate button at a push button station indicated by the numeral 41 in Fig. 1, thereby energizing the reel rotating motor 16.

Each arm 11 of one of the spiders 9 carries at the end thereof a mirror 42, which, in the vertical position shown in Fig. 1, reflects a beam from a light source 43 (which may be an ordinary electric light) into a photoelectric cell 44 which operates a relay shown in Fig. 5 of the drawings (to be presently described), thereby de-energizing the circuit of the motor 16 and stopping the rotation of the reel with the spare roll in the position shown in Fig. 1. Obviously the beam of light from the light source 43 will not be reflected into the photoelectric cell unless the mirror 42 on the reel arm 11 is in a given position, which position can of course be predetermined by the location of the light source and the photoelectric cell. This position is preferably such that the surface of the spare roll 15 will be about one to two inches 25 from the running web 33, although the exact position could of course be varied as might be desired. After reaching this position further depression of the positioning button will not cause any further rotation because the action of the 30 light beam on the photoelectric cell 44 prevents the completion of the circuit of the motor 16.

Upon release of the positioning button a belt drive motor 45 (which is electrically connected to a generator driven from the press in manner 35 which will be later described) is energized and, through a belt 46 taking over a pulley 47 on the motor shaft and a pulley 48 on a shaft 49 carrying a larger pulley 51, drives an endless belt 52 trained over said pulley 51 and a pulley 53 on a shaft 54, 40 said shafts 49 and 54 being journaled in bearing members 55 and 56, respectively, on a frame 57 which is pivotally supported at 58 from fixed frame members 59 depending from the press sub-structure 61. The downward movement of said belt frame 57 is limited by a hook 62 on the free 45 end of said frame adapted to cooperate with a stud 63 on one of said fixed frame members 59. The normal position of the belt 52 is thus in the path of the full rolls on the reel and when a roll 50 is brought to the position of the roll 15 in Fig. 1 it engages said belt, as shown in this figure, the point of engagement of the roll being preferably near one end thereof, although the point of contact might be varied or additional belts provided, 55 if desired.

When the motor 45 is energized, as previously stated, it drives the belt 52, which, in turn, rotates the roll, and since said motor 45 is operated by a press-driven generator the peripheral speed of the 60 incoming roll will be promptly brought to the speed of the running web 33.

Referring now to Fig. 3, it will be noted that the leading edge of the new roll, which is preferably cut on an angle as shown in this figure, 65 has glue applied thereto as indicated at 64, said edge being held to the roll by means of tabs 65, which are shown in detail in Fig. 3a, the forward ends of said tabs having adhesive on the underside thereof to cause the same to adhere to the roll 70 and the rear ends of said tabs having adhesive on the upper side thereof to cause them to adhere to the web. Said tabs are preferably cut to provide diagonal slits 66 to facilitate the tearing thereof after the paster is made. It will be noted 75 that space is left at the right of the glue, viewing

Fig. 3, for the belt 52, and if it were desired to locate the belt elsewhere, or to provide a plurality of belts, the glue would obviously be applied accordingly.

Secured to the periphery of the roll and projecting beyond one end thereof is a timing tab 67, 5 which may be of paper and which is adapted to intersect the path of the beam of light from the light source to the photoelectric cell 44 at a given point in the rotation of the roll. Said tab is preferably located immediately following the paste or 10 glue so that nearly a full revolution of the roll will be permitted after said tab intercepts the light beam for a purpose which will presently appear.

After the roll 15 starts rotating, the tab 67 of 15 course intercepts the light beam upon each rotation of the roll, thus momentarily energizing the relay in connection with the photoelectric cell 44 each time the beam is so intercepted, but this will have no effect unless the "paster" button has been 20 depressed by the operator. When the core is run down to the point where the operator desires to make a paster, he pushes this button which energizes a contact to produce rotation of the reel for the purpose of moving the new roll toward the 25 web 33. However, the circuit through the paster button contacts, as will appear from the description of the wiring diagram of Fig. 5, is not complete until the timing tab intercepts the beam of light to the photoelectric cell 44. The first 30 time a beam is intercepted by the tab after the paster button is depressed the circuit from the paster button contacts to the contactor for rotating the reel is closed and maintains its own holding circuit so that the new roll is moved toward the running web 33. As will later appear provision is made for operating the reel motor at this 35 time as a speed considerably higher than the normal speed in order that the contact between the roll and the web may be very quickly made.

A paster brush 68 is provided on the opposite side of the web, being formed in sections, as shown in Fig. 2, and is supported from a shaft 69 by means of vertical bars 71 connected by a cross bar 72. Said shaft 69 carries a sprocket 73 which is driven by a chain 74 taking over a sprocket 75 on the armature shaft 76 of a motor 77 which is adapted to be energized through the paster button contacts when the button is depressed and the light beam to the photoelectric cell 44 intercepted, as described in the preceding paragraph. This will cause the brush 68 to be moved inwardly simultaneously with the movement of the roll 15 from the position shown in Fig. 1 toward the web, thus effecting contact of 55 the new roll with the web in half the time which would be required through movement of the roll alone. Since the time element involved in bringing the web into contact with the roll is highly important, in view of the fact that this movement must be accomplished in a fraction of one revolution of the roll, this feature of the invention is of considerable practical importance. In view of the location of the tab 67 with reference to the glue, as hereinbefore mentioned, the roll 60 will be permitted to make nearly a full revolution after the tab intercepts the light beam and before the glue comes into contact with the web.

In the time required for this movement the web and roll will have been brought together and 70 will have traveled together for a considerable distance thus establishing a definite relationship before the glue 64 strikes the web. In this manner a much more satisfactory paster will be made than if the first contact between the web 75

and the roll were at or near the point on the latter where the glue is located. The pull of the running web will readily sever the tabs 65 after the paster is made, the tear starting with the slits 66, and the new web will continue into the press without slackening of the speed of the latter.

Mechanism is provided for severing the web from the expiring roll after the paster has been made, said means comprising a series of blades 78, which preferably have saw-toothed edges and which are carried by arms rigidly connected to a shaft 81 which is adapted to be turned by means of a small motor 82 mounted at the end thereof when said motor is energized in manner which will next be described.

A mirror 83 is mounted on an arm 84 secured to the frame substructure 61 and is preferably located between the position of the rotating roll 52 and the guide roller 34 over which the web passes in traveling to the press. In combination with this mirror, a second photoelectric cell, identified by the reference character 85, is employed, being adapted to be operated by a beam of light from a light source 86, which beam is reflected into said cell by means of said mirror 83. After the paster has been made, the tab 67 which is attached to the web of the new roll is carried past the mirror 83 and intercepts the light beam to said photoelectric cell 85, thereby operating a relay (to be later described) which, in turn, energizes the motor 82, which quickly turns the shaft 81, causing the saw-toothed blades 78 to sever the old web, this being accomplished practically simultaneously with the interception of the light beam by the tab in passing between said mirror 83 and its associated photoelectric cell.

Referring to the schematic wiring diagram shown in Fig. 5, there are provided four push buttons for controlling the circuits of the reel drive motor 16, the belt drive motor 45, the paster brush operating motor 77 and the sheet cut-off motor 81. This series of control buttons comprises: a stop button 88; a run button 89, which is mechanically interconnected with stop button 88; a positioning button 91; and a paster button 92. All of these buttons are located on the push button station 41 (Fig. 1) which is positioned at a convenient point near the reel.

Assuming that the operator wishes to start turning of the reel to carry a roll from loading position into the position occupied by roll 15 preparatory to making a paster, he first depresses run button 89 which closes the contacts of stop button 88 to supply current from a main line wire 93 through wires 94, 95 and 96 to the contacts of positioning button 91. Having thus preliminarily completed the circuit to the contacts of positioning button 91, the operator depresses the latter to supply current through a wire 97, a normally closed contactor 98, and a wire 99, to the coil 101 of a slow speed starting relay, the contacts of the latter being indicated at 102 and 103. The circuit from coil 101 is completed through a wire 104 to a wire 105, which connects with the other side of the main line supply. Depression of the positioning button 91 thus energizes coil 101 of the slow speed starting relay and closes contactors 102 and 103. The closing of the two last-mentioned contactors closes a circuit through the armature of reel drive motor 16. This armature circuit of motor 16 is traced from wire 93 through wires 106, 107, and 108 to contactor 102, thence through a wire 109 and a wire 110 to the motor armature. The return from

the motor armature is through a wire 111 and a wire 112 to contactor 103, thence through a wire 113 and a series field 115 to the other main line wire 105. The field circuit of motor 16 is traced from main line wire 93 through wire 106, a normally closed contactor 116, and a wire 117 to a field coil 118 and thence through a wire 119 to the other side of the line. The contactor 116 in its normally closed position short circuits a shunt field resistance 121. This shunt field resistance is short circuited by contactor 116 during all normal reel operations. As will presently appear, however, this resistance is inserted in the field of motor 16 to give the reel an increased speed of rotation during the making of the paster.

With positioning button 91 depressed, the reel continues to rotate at slow speed until the fresh roll moves into engagement with the drive belt 52, at which point one of the mirrors 42 reflects a beam of light from the source 43 into photoelectric cell 44. When this occurs an amplifier which is associated with cell 44 energizes a relay coil 122 which moves contactor 98 to open circuit position, thereby de-energizing coil 101 and stopping operation of reel drive motor 16. So long as one of the mirrors 42 reflects light into cell 44, coil 122 remains energized and holds contactor 98 and coil 101 in open circuit position, thereby preventing further rotation of the reel even though positioning button 91 be held in depressed position.

After the roll has been moved against belt 52 the operator releases positioning button 91, thereby closing a circuit through the upper contacts 36 of the positioning button to a wire 123 which connects through a contactor 124 and a wire 125 with the coil 126 of a belt drive motor relay, the contactors of which are indicated at 127 and 128. Contactor 124 will be in closed position at this time since it is operated by relay coil 122 which remains energized by photoelectric cell 44. When coil 120 is thus energized by the raising of the positioning button 91, it closes contactors 127 and 128 to complete the circuit between a press-driven alternating current generator 128 and belt drive motor 45. As will hereinafter appear, generator 128 is driven from the folder drive motor and since the frequency of the generated current determines the speed of motor 45, it follows that the belt 52 is thus accurately driven at such speed as will bring the spare roll up to the exact speed of the running web.

Each time the roll turns, it carries tab 67 across the beam of light which is directed onto mirror 42. The effect of this is to momentarily de-energize coil 122 to open contactor 124. Therefore, to avoid interruption of the circuit through coil 126, there is provided a holding circuit around contactor 124 which includes a wire 131 which connects through a wire 132 and a contactor 133 to a wire 134, the latter connecting with wire 123 which supplies current to contactor 124. As soon as current is supplied to wire 125 by the raising of positioning button 91, coil 126 is energized, as previously explained, and moves contactor 133 to closed position, thereby completing this holding circuit around contactor 124 and insuring that coil 126 will remain energized to maintain the circuit to the belt drive motor 45 regardless of the fluctuating movements of contactor 124.

After the spare roll has attained web speed, and when the running web is about to expire, the operator depresses paster button 92. The depression of the paster button closes a circuit from

the positioning button through wire 123, wire 134, contactor 133, and wire 132 to a wire 135, which connects through a contactor 136 and a wire 137 to the coil 138 of a high speed relay, the contactors of which are indicated at 139 and 141. Closing of the circuit through coil 138 moves contactors 139 and 141 to closed circuit position. These contactors, it will be noted, are connected in parallel with contactors 102 and 103 of the slow speed starting relay, and when closed complete a circuit through the armature of motor 16 in the same manner as described in connection with contactors 102 and 103. However, the motor is operated at this time at high speed inasmuch as the contactor 116 which short circuits field resistance 121 is moved to open circuit position by operation of the high speed starting relay. The effect of this is to insert shunt field resistance 121 in series with the field winding 118 thereby giving the reel an increased speed of rotation during the interval of the making of the paster.

At the same time that coil 138 is energized to close the high speed starting relay, brush operating motor 77 is energized to start movement of brush 68 against the running web. The relay which controls the circuit of motor 77 includes a coil 142 which is connected in circuit with wire 137, and a contactor 143 which in the closed position completes a circuit from main line wire 93 and a wire 164 to the armature of motor 77.

It will be noted that depression of the paster button will not close the circuits to motors 16 and 77 unless contactor 136 is in closed circuit position. This contactor is mounted upon the armature of relay coil 122 which is controlled by photoelectric cell 44. This coil, as previously explained, remains energized so long as light is reflected from mirror 42 into cell 44. With the spare roll in the position shown in Fig. 1, and rotating under the action of belt 52, this reflection of light to cell 44 is interrupted periodically by tab 67, which, it will be recalled, is positioned slightly behind the strip of paste 64. Each time tab 67 cuts across the ray of light passing to cell 44, coil 122 is momentarily de-energized and contactor 136 moves to closed circuit position. However, it remains in closed circuit position only for the instant during which the tab passes through the ray of light.

Regardless, therefore, of when the operator may depress the paster button, the circuit to motors 16 and 77 will not be closed until the tab 67 cuts through the beam of light passing to cell 44, and the spare roll will continue to rotate through nearly one full revolution before the paste comes opposite the expiring web. There is thus provided ample time for movement of the spare roll toward the running web and also for movement of brush 68 against the web before the paste comes into contact with the web. A holding circuit is provided for coil 138 so that once the latter has been energized by momentary closing of contactors 136, it will remain in such condition regardless of the position of said contactor. This holding circuit comprises a wire 145 which connects to coil 138 through a contactor 146. As soon as coil 138 is energized by the depression of the paster button and the closing of contactor 136, it pulls contactor 146 to closed circuit position, thereby maintaining a circuit through the paster button to coil 138 regardless of whether contactor 136 be open or closed.

Current to sheet cut-off motor 82 is supplied from wire 135 to a wire 147 which connects through a contactor 148 with the armature cir-

cuit of the motor, the return to the main line being through a wire 149. Inasmuch as wire 135 is supplied from the main line through paster button 92, current will be supplied to contactor 148 so long as the paster button is depressed. Contactor 148 is operated by a coil 151 which is energized through an amplifier associated with photoelectric cell 85. Coil 151 remains energized so long as a beam of light passes from mirror 83 to cell 85. As soon as the paster has been made tab 67 passes upwardly, as hereinbefore explained, to interrupt this beam of light to cell 85. Coil 151 is thus momentarily de-energized by this action and allows contactor 148 to close, thereby energizing sheet cut-off motor 82. As soon as the flow of light to cell 85 is re-established, coil 151 is again energized and opens the circuit to the cut-off motor.

After the pasting and severing operations have been completed, the operator continues to hold the paster button depressed until the reel has carried the newly substituted roll into running position, at which time the paster button is released and the reel comes to rest with the active roll in normal running position.

The use of a press-driven alternating current generator for supplying current to the belt drive motors 45 is advantageous not only because it insures that the spare rolls will be brought to exactly the speed of the running web, but because it readily permits the motors to be associated with the particular folder which happens to be receiving the webs from a selected group of printing units. The electrical connections for accomplishing this are diagrammatically shown in Fig. 35. In this figure the several press units are indicated generally at 152, and a pair of adjacent folders are indicated at 153 and 154. The folders are provided with individual drive motors 155 and the alternating current generators 129, which supply belt drive motors 45, are driven from folder drive shafts 156 through bevel gears 157 and 158. The circuits of the several motors 45 are provided with two-way switches 159 whereby said motors may be connected with one or the other of a pair of bus bars 161 and 162, the connection with bar 161 being effected by throwing said switches to the right, and the connection with the bar 162 being effected by throwing said switches to the left. Current to bus bar 161 is supplied from the generator 129 which is associated with folder 153. Similarly current to bus bar 162 is supplied from the generator 129 which is associated with folder 154. A simple adjustment of switches 159 thus serves to connect the motors 45 for operation in conjunction with either one or the other of the generators 129. Commutation to a greater number of generators than the two illustrated might be provided for, in manner which will be apparent to those skilled in the art, if desired.

The foregoing detailed description has been given for clearness of understanding only, and no unnecessary limitations should be understood therefrom, but the appended claims should be construed as broadly as permissible in view of the prior art.

I claim:

1. In apparatus of the character described, the combination of movable means for supporting a plurality of rolls of paper, means for moving a fresh roll toward the traveling web from an expiring roll, means including a light-sensitive device and means carried by the roll support for causing operation of said device when said roll

support reaches a certain position for stopping said fresh roll a predetermined distance from said web, means for rotating said fresh roll to bring it to web-speed, and means for effecting contact of the fresh roll and the traveling web from the expiring roll.

2. In apparatus of the character described, the combination of movable means for supporting a plurality of rolls of paper, means for moving a fresh roll toward the traveling web from an expiring roll, means, including a light-sensitive device and a source of light cooperatively related thereto, for stopping said fresh roll a predetermined distance from said web, means for rotating said fresh roll to bring it to web-speed, and means for effecting contact of the fresh roll and the traveling web from the expiring roll, said last-mentioned means being controlled by interruption of the beam of light which operates said light-sensitive device.

3. In apparatus of the character described, the combination of movable means for supporting a plurality of rolls of paper, means for moving a fresh roll toward the traveling web from an expiring roll, means including an automatic electric device controlled by the position of said roll supporting means but having no mechanical contact therewith or with the roll for stopping said fresh roll a predetermined distance from said web, means for rotating said fresh roll to bring it to web-speed, and means for effecting contact of the fresh roll and the traveling web from the expiring roll.

4. In apparatus of the character described, the combination of movable means for supporting a plurality of rolls of paper, means for moving a fresh roll toward the traveling web from an expiring roll, means including a light-sensitive device and a source of light cooperatively related thereto, for stopping said fresh roll a predetermined distance from said web, means for rotating said fresh roll to bring it to web-speed, and means for effecting contact of the fresh roll and the traveling web from the expiring roll, said last-mentioned means being controlled by interruption of the beam of light which operates said light-sensitive device and including means for moving said web toward the fresh roll simultaneously with movement of said roll toward the web.

5. In apparatus of the character described, the combination of movable means for supporting a plurality of rolls of paper, means for moving a fresh roll toward the traveling web from an expiring roll, means including a light-sensitive device and means carried by the roll support for causing operation of said device when said roll support reaches a certain position for stopping said fresh roll a predetermined distance from said web, means for rotating said fresh roll to bring it to web-speed, means for effecting contact of the fresh roll and the traveling web from the expiring roll causing the leading edge of the web on the fresh roll, having adhesive thereon, to be pasted to said traveling web, and means automatically operative after the pasting between said webs has traveled a predetermined distance for cutting off said web from the expiring roll.

6. In apparatus of the character described, the combination of movable means for supporting a plurality of rolls of paper, means for moving a fresh roll toward the traveling web from an expiring roll, means for rotating said fresh roll to bring it to web-speed, means for effecting contact of the rotating fresh roll and the traveling

web from the expiring roll causing the leading edge of the web on the fresh roll, having adhesive thereon, to be pasted to said traveling web, and means including a light-sensitive control device controlled by the travel of the web and automatically operative after the pasting between said webs has traveled a predetermined distance for cutting off said web from the expiring roll.

7. In apparatus of the character described, means for making high speed pasters, comprising a movable support for a running roll and a spare roll, means for moving said support preparatory to making a roll change, means, including a light-sensitive device and a source of light cooperatively related thereto, for stopping the movement of the support with the spare roll spaced a predetermined distance from the web proceeding from the running roll to the press, means for starting rotation of the spare roll, said roll being provided with means adapted, when the roll is rotated, to interrupt the beam of light which operates said light-controlled means, and means operative upon the interruption of said light to further move said support to effect contact of the spare roll with the traveling web from the expiring roll.

8. In apparatus of the character described, the combination of movable means for supporting a plurality of rolls of paper, means for moving a fresh roll toward the traveling web from an expiring roll, and means other than the roll support for simultaneously moving the web toward the roll prior to contact of the roll with the web to thereby effect contact between said roll and web.

9. In apparatus of the character described, the combination of movable means for supporting a plurality of rolls of paper, means for driving a fresh roll to rotate the same and bring it up to the speed of the traveling web from an expiring roll, means for effecting contact of the rotating fresh roll and the traveling web from the expiring roll, and means, including a light-sensitive controlling device controlled by the travel of the web, for cutting off said expiring web.

10. In apparatus of the character described, the combination of movable means for supporting a plurality of rolls of paper, means for driving a fresh roll having adhesive thereon to rotate the same and bring it up to the speed of the traveling web from an expiring roll, means for effecting contact of the rotating fresh roll and the traveling web from the expiring roll to make a paster, and means, including a light-sensitive controlling device controlled by the travel of the web, for cutting off said expiring web in timed relationship to the pasting operation.

11. In apparatus of the character described, the combination of movable means for supporting a plurality of rolls of paper, means for effecting contact of a fresh roll having adhesive thereon with the web from an expiring roll to make a paster, and means including a light-sensitive device controlled by the travel of the web for cutting off said expiring web a predetermined distance behind the paster.

12. In apparatus of the character described, a magazine reel adapted to carry a plurality of rolls of paper, means for rotating said reel to bring a spare roll thereon into position adjacent the traveling web from an expiring roll, means for rotating the spare roll to bring it to web-speed, the leading edge of the web of said spare roll having adhesive thereon, and means for effecting

5 contact of the spare roll and the traveling web from the expiring roll, including light-controlled means for timing the relative movement of the web and the spare roll with reference to the rotation of said roll to insure initial contact of the web with the roll at a point on the latter well in advance of the adhesive.

10 13. In apparatus of the character described, the combination of movable means for supporting a plurality of rolls of paper, means for driving a fresh roll having adhesive thereon to rotate the same and bring it up to the speed of the traveling web from an expiring roll, means for effecting contact of the rotating fresh roll and the traveling web from the expiring roll to make a paster, and means, including a light-sensitive controlling device for cutting off said web, said means for effecting contact of said roll and web comprising a light-sensitive device for normally preventing the final relative movement of said traveling web and spare roll and an element carried by said roll for interrupting, at a predetermined point in the rotation of said roll, a light beam which operates said light-sensitive device, thereby causing the latter to become ineffective to further prevent said final relative movement of said web and roll.

15 14. In apparatus of the character described, the combination of movable means for supporting a plurality of rolls of paper, means for moving a spare roll into position adjacent the running web from an expiring roll, means for stopping the motion of said movable means with the spare roll a predetermined distance from the running web, the end of the web of said roll having adhesive thereon, means for rotating said spare roll, and light-controlled means for effecting contact between the spare roll and the running web, said means becoming effective when said adhesive on the web of the new roll is a substantial distance away from the point of contact with the running web, whereby time is allowed for effecting engagement between the roll and the running web before the adhesive on said roll arrives at the point of contact with said running web.

20 25 15. In apparatus of the character described, a magazine reel for carrying a plurality of rolls of paper, means for turning said reel to position a spare roll a predetermined distance from the

25 traveling web from an expiring roll, means for rotating the spare roll to bring it up to web speed, and means for thereafter rotating the reel to effect contact between the rotating spare roll and said traveling web, said means including electrical devices automatically operable upon the starting of such rotation to accelerate the speed of said reel turning means.

30 16. In apparatus of the character described, the combination of movable means for supporting a plurality of rolls of paper, means for effecting contact of a fresh roll having adhesive thereon with the web from an expiring roll to make a paster, and means including a light-sensitive device controlled by the travel of the web for cutting off said expiring web behind the paster.

35 20 25 17. In apparatus of the character described, the combination of movable means for supporting a plurality of rolls of paper, and means, including a light-sensitive device and a source of light cooperatively related thereto, for moving said supporting means to place a new roll in suitable relation to the web proceeding from an expiring roll to make a paster, attaching the web of the new roll to the expiring web, the web on said roll having a flag attached thereto for controlling the beam of light operating said device to thereby cause contact of the roll and web at a predetermined point in the rotation of said roll to effect said paster.

40 30 35 40 45 18. In apparatus of the character described, the combination of movable means for supporting a plurality of rolls of paper, means, including a light-sensitive device and a source of light cooperatively related thereto, for moving said supporting means to place a new roll in suitable relation to the web proceeding from an expiring roll to make a paster, attaching the web of the new roll to the expiring web, the web on said roll having a flag attached thereto for controlling the beam of light operating said device to thereby cause contact of the roll and web at a predetermined point in the rotation of said roll to effect said paster, and means, including a light-sensitive device, controlled by said flag at a predetermined point after it has left the roll to cut off the expiring web.

HAROLD L. McCLEERY.
